STABILIZATION OF ORGANIC COMPOUNDS

Ralph B. Thompson and Joseph A. Chenicek,
Riverside, Ill., assignors to Universal Oil Products Company, Chicago, Ill., a corporation of Delaware

No Drawing. Application January 29, 1948,
Serial No. 5,210

13 Claims. (Cl. 99—163)

1

This invention relates to the stabilization of organic compounds which tend to deteriorate in storage or in use due to oxidation reactions.

Various organic compounds are unstable in storage or during treatment and form undesirable gums, undergo discoloration, form sludges or otherwise deteriorate due to oxidation, polymerization or other undesired reactions. Included among the organic compounds which undergo such deterioration are gasoline, Diesel oil, mineral oil, lubricating oil, fuel oil, drying oil, greases, edible fats and oils, acetylenes and particularly vinyl acetylene, butadiene, isoprene, styrene and other vinyl aromatics, various unsaturated alcohols, acids, ketones, etc.

The invention is particularly applicable to the stabilization of unsaturated gasolines and particularly cracked and polymer gasolines. In storage or during treatment these unsaturated gasolines tend to form undesirable gums. The invention is also applicable to the treatment of aviation gasolines which tend to undergo deterioration due to the addition of tetraethyl lead fluid or due to other components in the gasoline.

The invention is also particularly applicable to the stabilization of edible fats and oils which generally are of animal or vegetable origin and which tend to become rancid, especially during long periods of storage prior to use. Typical representatives of these edible fats and oils include linseed oil, menhaden oil, cod liver oil, castor oil, olive oil, rapeseed oil, coconut oil, palm oil, corn oil, sesame oil, peanut oil, babassu oil, butter, fat, lard, beef tallow, etc. It is understood that other oils and fats may be treated within the scope of the present invention, including oils and fats which previously have been subjected to various treatments, such as blowing with air, heat treatment, etc.

In another embodiment the present invention is particularly applicable to the treatment of crops by dusting or spraying in order to preserve food accessory factors such as carotene, vitamins, various fatty acids, alcohols, etc.

In one embodiment the present invention relates to a method of stabilizing an organic material subject to oxidative deterioration which comprises adding thereto an inhibitor comprising a tricyclic compound, two rings being six-membered alicyclic rings, at least one of said rings comprising a hydroxy substituted benzene ring, said benzene ring being fused to a ring selected from the group consisting of dihydro furan and dihydro pyran rings.

In a specific embodiment the present invention

5 relates to a method of stabilizing motor fuel normally tending to deteriorate in storage which comprises adding thereto from about 0.001% to about 0.5% by weight of 2,2-dimethyl-5-hydroxy-2,3,6,7,8,9-hexahydronaphtho-(1,2-b)-furan.

In another specific embodiment the present invention relates to a method of stabilizing edible fats and oils against rancidity which comprises adding thereto from about 0.001% to about 0.5% by weight of 2,2,7-trimethyl-5-hydroxy-2,3,6,9-tetrahydronaphtho-(1,2-b)-furan.

In another embodiment the present invention relates to organic compounds normally tending to deteriorate in storage, and particularly motor fuel or edible fats and oils, containing a small amount of the inhibitors herein set forth.

In accordance with the present invention, stabilization of unstable organic compounds is effected by adding thereto a small amount of a 15 particular class of inhibitors which are illustrated by the following general structures:

R, R1, R2 and/or R3 comprise hydrogen or alkyl radicals. When these groups comprise alkyl rad-

icals, they preferably are selected so that the total number of carbon atoms in the inhibitor does not exceed about 25. Still more particularly these compounds preferably comprise alkyl radicals containing from 1 to about 4 carbon atoms and include such groups as ethyl, methyl, propyl and butyl.

In the subsequent disclosure of specific compounds, the system of numbering is in conformity with the following:

General structure I above illustrates a 5-hydroxy-2,3-dihydronaphtho-(1,2-b)-furan. Particularly satisfactory inhibitors of this class include such compounds as 5-hydroxy-2,3-dihydronaphtho-(1,2-b)-furan, 2,2-dimethyl-5-hydroxy-2,3-dihydronaphtho-(1,2-b)-furan, 2,2,7-trimethyl-5-hydroxy-2,3-dihydronaphtho-(1,2-b)-furan, etc.

Structure II illustrates a 6-hydroxy-3,4-dihydronaphtho-(1,2-b)-pyran. Particularly satisfactory inhibitors of this class include such compounds as 6-hydroxy-3,4-dihydronaphtho-(1,2-b)-pyran, 2,2-dimethyl-6-hydroxy-3,4-dihydronaphtho-(1,2-b)-pyran, 2,2,8-trimethyl-6-hydroxy-3,4-dihydronaphtho-(1,2-b)-pyran, etc.

Structure III illustrates a 5-hydroxy-2,3,6,9-tetrahydronaphtho-(1,2-b)-furan. Particularly satisfactory inhibitors of this class include such compounds as 5-hydroxy-2,3,6,9-tetrahydronaphtho-(1,2-b)-furan, 2,2-dimethyl-5-hydroxy-2,3,6,9-tetrahydronaphtho-(1,2-b)-furan, 2,2,7-trimethyl-5-hydroxy-2,3,6,9-tetrahydronaphtho-(1,2-b)-furan, etc.

Structure IV illustrates a 6-hydroxy-3,4,7,10-tetrahydronaphtho-(1,2-b)-pyran. Particularly satisfactory inhibitors of this class include such compounds as 6-hydroxy-3,4,7,10-tetrahydronaphtho-(1,2-b)-pyran, 2,2-dimethyl-6-hydroxy-3,4,7,10-tetrahydronaphtho-(1,2-b)-pyran, 2,2,8-trimethyl-6-hydroxy-3,4,7,10-tetrahydronaphtho-(1,2-b)-pyran, etc.

Structure V illustrates a 5-hydroxy-2,3,6,7,8,9-hexahydronaphtho-(1,2-b)-furan. Particularly satisfactory inhibitors of this class include such compounds as 5-hydroxy-2,3,6,7,8,9-hexahydronaphtho-(1,2-b)-furan, 2,2-dimethyl-5-hydroxy-2,3,6,7,8,9-hexahydronaphtho-(1,2-b)-furan, 2,2,7-trimethyl-5-hydroxy-2,3,6,7,8,9-hexahydronaphtho-(1,2-b)-furan, etc.

Structure VI illustrates a 6-hydroxy-3,4,7,8,9,10-hexahydronaphtho-(1,2-b)-pyran. Particularly satisfactory inhibitors of this class include such compounds as 6-hydroxy-3,4,7,8,9,10-hexahydronaphtho-(1,2-b)-pyran, 2,2-dimethyl-6-hydroxy-3,4,7,8,9,10-hexahydronaphtho-(1,2-b)-pyran, 2,2,8-trimethyl-6-hydroxy-3,4,7,8,9,10-hexahydronaphtho-(1,2-b)-pyran, etc.

It is understood that the compounds hereinbefore set forth comprise preferred inhibitors and that compounds of these general structures substituted by suitable groups are also combined within the scope of the present invention. However, as hereinbefore set forth, it is preferred that the total number of carbon atoms in the inhibitor does not exceed about 25.

It is understood that the inhibitors of the present invention may comprise the specific compounds named herein in admixture with various isomers thereof. For example, in the dihydro compound the isomers may comprise corresponding compounds in which the double bond in the non-aromatic alicyclic ring has shifted to a non-conjugated position and/or those in which the hydroxy group and furan or pyran ring have interchanged positions with respect to an alkyl group positioned on the non-aromatic alicyclic ring. In the other two types of compounds, the isomers will be of the latter type.

The inhibitors of the present invention may be prepared in any suitable manner. In one method of preparing 2,2-dimethyl-5-hydroxy-2,3,6,7,8,9-hexahydronaphtho-(1,2-b)-furan, 1,4-dihydroxy-5,6,7,8-tetrahydronaphthalene is dissolved in an aqueous organic solvent containing an alkaline material and is reacted with methallyl chloride. The reaction is effected by boiling under refluxing conditions, after which the product may be acidified and extracted with organic solvents. The unreacted starting material may be separated by extraction with dilute aqueous caustic solution and the monomethallyl ether may be recovered by extraction with Claisen solution. The monomethallyl ether is isomerized by boiling with dimethylaniline or the like, the dimethylaniline is removed with dilute acid, and ring closure is effected by boiling with a suitable acid such as 90% formic acid. The acid is then removed by distillation and the product is purified by distillation in vacuum. The other naphtho furans may be prepared in substantially the same manner, but varying the starting reagents as desired.

2,2-dimethyl-6-hydroxy-3,4,7,8,9,10-hexahydronaphtho-(1,2-b)-pyran may be prepared by warming a suspension of 1,4-dihydroxy-5,6,7,8-tetrahydronaphthalene and isoprene in a suitable solvent, such as glacial acetic acid which has been saturated with anhydrous hydrogen chloride. After the reaction has proceeded to completion, the product is extracted with an organic solvent, such as ether-petroleum ether, and the acetic acid is removed by treatment with a suitable base such as sodium bicarbonate. The unreacted starting material may be removed by extraction with a dilute aqueous caustic solution and the final product may be purified by distillation under vacuum.

When it is desired to add other alkyl group or groups to either one or both of the rings, it may be effected in any suitable manner. For example, butylation may be effected by dissolving the hydronaphtho furan or pyran in acetic acid and adding thereto a suitable catalyst such as 85% phosphoric acid. Tertiary butyl alcohol is then added and the mixture may be heated to a temperature of 60-85° C. with constant stirring, after which the product may be poured into water, extracted first with organic solvents and then with Claisen solution and finally distilled in vacuum.

The inhibitor of the present invention is generally added to organic materials in an amount of less than 1% by weight and generally within the range of from about 0.001% to about 0.5%. When used in gasoline, it is understood that the inhibitor may be used in conjunction with various dyes, metal deactivators, anti-knock agents such as tetraethyl lead, etc. When used in edible fats and oils it is understood that the inhibitor may

be used in conjunction with a synergist, such as phosphoric acid, ascorbic acid, etc.

The following examples are introduced to further illustrate the novelty and utility of the present invention but not with the intention of unduly limiting the same.

The inhibitors used in the following runs were prepared in a manner similar to that heretofore set forth.

EXAMPLE I

The following runs were made with a lard which had a normal stability period of 3½ hours as determined by the Swift test. This test is described in detail in the article by A. E. King, H. L. Roschen and W. H. Irwin, which appeared in the Oil and Soap, vol. X, No. 6, pages 105 to 109, (1933). In general, this test comprises bubbling air through a sample of the lard and reporting the number of hours until the lard develops a peroxide value of 20.

0.02% by weight of the inhibitor was added to different samples of the lard and gave the results as shown in Table 1.

Table 1

Inhibitor	Stability Period, Hours
2,2,7-trimethyl-5-hydroxy-2,3,6,9-tetrahydronaphtho-(1,2-b)-furan	50
2,2-dimethyl-5-hydroxy-2,3,6,7,8,9-hexahydronaphtho-(1,2-b)-furan	23
2,2,7-trimethyl-5-hydroxy-2,3,6,7,8,9-hexahydronaphtho-(1,2-b)-furan	31
2,2-dimethyl-6-hydroxy-3,4,7,8,9,10-hexahydronaphtho-(1,2-b)-pyran	32
2,2,8-trimethyl-6-hydroxy-3,4,7,8,9,10-hexahydronaphtho-(1,2-b)-pyran	32

It will be noted from the data in the above table that the various inhibitors of the present invention considerably increased the stability period of the lard.

EXAMPLE II

The following tests were made with a Pennsylvania cracked gasoline which had an uninhibited induction period of 100 minutes. 0.025% by weight of inhibitor was added to different samples of the gasoline and gave the results as shown in Table 2.

Table 2

Inhibitor	Induction Period, Minutes
2,2,7-trimethyl-5-hydroxy-2,3,6,9-tetrahydronaphtho-(1,2-b)-furan	485
2,2-dimethyl-5-hydroxy-2,3,6,7,8,9-hexahydronaphtho-(1,2-b)-furan	805
2,2,7-trimethyl-5-hydroxy-2,3,6,7,8,9-hexahydronaphtho-(1,2-b)-furan	690
2,2-dimethyl-6-hydroxy-3,4,7,8,9,10-hexahydronaphtho-(1,2-b)-pyran	435
2,2,8-trimethyl-6-hydroxy-3,4,7,8,9,10-hexahydronaphtho-(1,2-b)-pyran	500

It will be noted from the data in the above table that the inhibitors of the present invention considerably increased the induction period of the gasoline.

We claim as our invention:

1. A method of stabilizing motor fuel normally tending to deteriorate in storage which comprises adding thereto a 5-hydroxy-2,3,6,9-tetrahydronaphtho-(1,2-b)-furan.

2. A method of stabilizing motor fuel normally tending to deteriorate in storage which comprises

adding thereto a 5-hydroxy-2,3,6,7,8,9-hexahydronaphtho-(1,2-b)-furan.

3. A method of stabilizing cracked gasoline which comprises adding thereto from about 0.001% to about 0.5% by weight of 2,2-dimethyl-5-hydroxy-2,3,6,7,8,9-hexahydronaphtho-(1,2-b)-furan.

4. A method of stabilizing edible fats and oils against rancidity which comprises adding thereto an inhibitor comprising a 5-hydroxy-2,3,6,7,8,9-hexahydronaphtho-(1,2-b)-furan.

5. A method of stabilizing edible fats and oils against rancidity which comprises adding thereto an inhibitor comprising a 5-hydroxy-2,3,6,9-tetrahydronaphtho-(1,2-b)-furan.

6. A method of stabilizing lard which comprises adding thereto from about 0.001% to about 0.5% by weight of 2,2,7-trimethyl-5-hydroxy-2,3,6,9-tetrahydronaphtho-(1,2-b)-furan.

7. An organic material normally subject to oxidative deterioration containing, as an inhibitor for said deterioration, a small amount of a 5-hydroxy-2,3,6,9-tetrahydronaphtho-(1,2-b)-furan.

8. An organic material normally subject to oxidative deterioration containing, as an inhibitor for said deterioration, a small amount of a 5-hydroxy-2,3,6,7,8,9-hexahydronaphtho-(1,2-b)-furan.

9. Cracked gasoline containing from about 0.001% to about 0.5% by weight of 2,2-dimethyl-5-hydroxy-2,3,6,7,8,9-hexahydronaphtho-(1,2-b)-furan.

10. Edible fats and oils normally tending to become rancid containing from about 0.001% to about 0.5% by weight of 2,2,7-trimethyl-5-hydroxy-2,3,6,9-tetrahydronaphtho-(1,2-b)-furan.

11. Edible fats and oils normally tending to become rancid containing, as an inhibitor to retard rancidity development, a 5-hydroxy-2,3,6,9-tetrahydronaphtho-(1,2-b)-furan.

12. A method of stabilizing an organic material normally subject to oxidative deterioration which comprises adding thereto an inhibitor comprising a tricyclic compound containing the naphthalene ring system having fused to one of its benzene rings, by a carbon atom and a heterocyclic oxygen atom, a member of the group consisting of dihydro furan and dihydro pyran rings, said one benzene ring having a hydroxy group in the position para to said heterocyclic oxygen atom.

13. An organic material normally subject to oxidative deterioration containing, as an inhibitor for said deterioration, a small amount of a tricyclic compound containing the naphthalene ring system having fused to one of its benzene rings, by a carbon atom and a heterocyclic oxygen atom, a member of the group consisting of dihydro furan and dihydro pyran rings, said one benzene ring having a hydroxy group in the position para to said heterocyclic oxygen atom.
